LOW VELOCITY TELEVISION TRANSMITTING APPARATUS

Albert Rose, East Orange, N. J., assignor to Radio Corporation of America, a corporation of Delaware

Application August 27, 1942, Serial No. 456,344

10 Claims. (Cl. 250—150)

1

My invention relates to television transmitting tubes and particularly to tubes utilizing low velocity electron scanning beams.

In the operation of a television transmitting tube of the low velocity electron beam scanning type including a target or mosaic electrode with an oppositely disposed electron gun and a combination of magnetic-electrostatic deflection means, the electrons of the scanning beam which do not reach the target because of their low velocity return to a collecting electrode at the surface of which they may produce secondary electrons. It has been customary to utilize a signal plate comprising a portion of the target electrode from which the signal may be taken although the signal may be derived from the collecting electrode. With this latter arrangement, it is advantageous to provide means for developing secondary electrons, such as shown by Iams in his U. S. Patent 2,288,402.

The requirements to be met in the design of a television transmitting tube incorporating an electron multiplier for amplifying the return portion of the scanning beam differ in one important respect from the requirements for the usual electron multiplier in that in such a television tube the virtual point of origin varies in accordance with the scanning of the target and consequently in conventional structures, such as shown by Iams, the returning beam strikes at various points on the first electrode of the multiplier. If exceptional care is not taken in preparing the multiplier electrodes, some distortion may be introduced in this type of structure.

Accordingly it is an object of my invention to provide a structure of the television transmitting low velocity multiplier type wherein more uniform secondary amplification may be obtained. It is another object to provide such a structure wherein the multiplier electrodes may be more easily processed. It is another object to provide a structure wherein distortion produced by non-uniformity of secondary electron emitting surfaces is minimized. It is still another object of my invention to provide a tube wherein the electrodes may be made of such form and shape as to minimize introduction of distortion and a structure wherein the overall length of the tube may be decreased.

In accordance with my invention an electrostatic image corresponding in electrostatic energy distribution to an optical image is formed on a target preferably of the photo-sensitive mosaic type which is scanned in two mutually perpendicular directions by wholly magnetic means, the

2

electrons of the beam being incident upon the target in accordance with the electrostatic charges thereon so that electrons not reaching the target are returned along substantially the same paths as the scanning beam to an electron multiplier made in accordance with my invention. The said electron multiplier preferably comprises an electrode or electrodes symmetrically surrounding the initial beam path immediately following its formation as a beam and prior to its deflection by wholly magnetic means. More particularly in accordance with my invention I provide a structure comprising a cylinder, truncated cone, annular electrode or a plurality of such electrodes directly adjacent the point of the final beam formation and between said point and the deflection means. Such points of beam formation may be defined as the point where the cross-sectional areas of the beam is limited and at which the beam has its minimum diameter.

The objects mentioned above as well as other objects, features, and advantages of my invention will be apparent when considered in view of the following description taken in connection with the accompanying drawing in which:

Figure 1 is a longitudinal cross-sectional view of television transmitting apparatus made in accordance with my invention; and

Figures 2 and 3 show modified forms of certain of the electrodes shown in Figure 1.

In general, the apparatus of my invention comprises an evacuated envelope having a target preferably of the photo-sensitive mosaic type at one end thereof and an electron source and an anode oppositely disposed therefrom to develop and project upon the target an electron beam constrained along its path by a longitudinal magnetic field and deflected over the target by magnetic means, such a plurality of magnetic coils developing fields normally intersecting one another so that the mosaic electrode may be scanned in mutually perpendicular directions. The electron source may be of the conventional type comprising a small area cathode surrounded by a conventional apertured grid for purposes of electron beam intensity control being followed in the direction toward the target by an anode having a beam limiting aperture. This aperture defines the minimum electron cross-section and diameter and is necessarily small to prevent returning electrons from approaching the cathode, which electrons might be redirected to the target. Immediately adjacent this defining apertured anode and between this anode and the deflection means I provide symmetrical means surrounding the

electron beam path to collect secondary electrons which may be developed by returning electrons impinging the anode or a series of such electrodes for developing additional secondary electrons and collecting these electrons for the development of the television signals.

Referring particularly to my tube structure and its associated apparatus as shown in Figure 1, the tube comprises an elongated evacuated envelope 1 enclosing at one end thereof a target or mosaic electrode 2 and at the opposite end an electrode assembly 3 adapted to develop, limit, define and project an electrode beam toward the mosaic electrode such as along the path 4 shown by the dashed line. This path will be referred to as the "initial electron path." The mosaic electrode is preferably of the type described in my U. S. Patent No. 2,213,176 and includes a sheet of insulation, such as mica sheet 5, having on its rear surface a semi-transparent electrically conducting condenser plate 6, usually referred to but not used as a signal plate, and on the front surface a mosaic of mutually insulated and separated photo-sensitive particles 7. Various methods of manufacturing such electrodes are well known in the art and obviously photo-conductive or photo-voltaic targets may be utilized if desired. The electrode structure 3 at the opposite end of the envelope 1 comprises a cathode 10 from which electrons may be drawn, a control electrode 11 connected to the usual biasing battery and an anode 12 having a beam defining aperture 13, this anode being maintained positive with respect to the cathode 10 by a potential source 14 to accelerate the electron beam along the initial electron path 4. The beam defining aperture determines the minimum cross-section of the beam and substantially prevents electrons not reaching the target from entering the space between the cathode and anode as appears more particularly hereinafter. Preferably the cathode 10 is connected directly to the condenser plate 6 of the mosaic electrode so that electrons approaching the mosaic are decelerated to substantially zero velocity, these electrons being collected or rejected by the mosaic in accordance with the intensity charges thereon developed by light representative of an optical image.

To direct the electron beam in a focused condition between the beam defining apertured anode 12 and target, I provide a focusing coil 16 wholly enclosing and preferably extending beyond the space between the anode 12 and the target 2. This focusing coil is so designed as to develop a longitudinal magnetic field strength of approximately 50-75 gauss which I have found sufficient to maintain the electron beam in a focused condition. Due to the presence of this field the electrons of the beam passing through the beam defining apertured anode with initial transverse velocity follow helical paths having a number of focal points along the beam path so that while I have referred to focusing of the beam, it will be appreciated that the beam has a number of focal points along the beam path, the potential between the anode and cathode in combination with the strength of the magnetic field being so proportioned as to develop a beam focal point preferably in the plane of or on the surface of the target 2. In addition I provide, preferably spaced between the beam limiting apertured anode and the target, magnetic means to deflect the beam in two mutually perpendicular directions such as two sets of magnetic deflection coils 17 and 18. The coils 17 are shown displaced

90° from their actual operating position for the sake of clarity in the drawing. However, the coils 17 and 18 may be superposed, in which case the tube may be made somewhat shorter.

5 In operation of the structure so far described the electron beam follows an initial path 4 parallel with the longitudinal magnetic field developed by the coil 16 until under the influence of the deflection coils 17 and 18 the beam is deflected and 10 scanned over the target 2. Electrons of the beam are collected in accordance with the electrostatic charges developed by the optical image light and electrons not being collected by the mosaic then return in the direction of the electrode structure 3 over a return path 4a. Neglecting the transit time of the electrons, inasmuch as their relative velocity is high in comparison with the rate of change of deflection, the electrons follow substantially the same path while 15 returning as while approaching the target. I have found that the return path deviates from the initial path and follows paths surrounding the initial path depending on the deflection at any instant of time. Consequently, the great majority of the returning electrons become incident 20 upon the anode 12, very few passing through the beam limiting aperture 13 because of its small diameter and because of the divergence between the initial and return paths.

25 In accordance with my invention, I provide the beam limiting apertured anode 12 of secondary electron emitting material so that as the returning electrons are reaccelerated by the anode 12, they impinge thereon and develop secondary 30 electrons, and I provide means symmetrically surrounding the electron beam path to collect these secondary electrons or produce further secondaries which are then collected. Referring again to Figure 1, I have shown a cylindrical 35 electrode 20 immediately between the beam limiting apertured anode 12 and the first set of deflection coils 17. The electrode 20 is preferably maintained slightly positive with respect to the anode 12 to provide a field capable of collecting 40 secondary electrons from the anode 12. Any secondary electrons which may be emitted on the surface of the electrode 20 are likewise collected. Thus, the electrode 20 may be supplied from the potential source 14 through an output impedance 45 21 so that the signal developed across this impedance by electrons being collected may be applied to a translating device such as the amplifier 22. From this showing of Figure 1, it will be 50 seen that the cylindrical electrode 20 is positioned 55 symmetrically with respect to the going electron beam and likewise with respect to the returning electrons so that electrons returning from any portion of the target are amplified in accordance with the secondary emitting properties of the anode 12 and uniformly collected by the electrode 20. The material of the anode, at least over the surface exposed to the target 2, preferably has 60 high secondary electron emitting properties. Thus, the anode 12, as well as other electrodes provided for secondary electron multiplication 65 may be such as described by Leverenz et al., U. S. Patent 2,233,276.

A further advantage results from the use of my improved construction in that further secondary electron emission may be obtained by interposing an electron permeable perforated electrode between the secondary electron paths and the electrode 20. Thus, I have shown a cylindrical wire mesh electrode 23 which may be operated at a higher potential than the electrode 20 if a second

stage of electron multiplication is desired, in which event, the output impedance is connected in the mesh electrode circuit to the potential source 14. However, improved operation is obtained even for single electron multiplication utilizing the mesh electrode 23 connected to the electrode 20 as shown at 24.

I have found in operating apparatus of the type described that secondary electrons liberated by the anode 12 or other electrodes adjacent thereto may flow in the direction of the mosaic electrode and escape the field developed by the electrodes 20 or 23, and I therefore provide a trap for these electrons comprising an electrode 25 preferably of annular form having a relatively large aperture aligned with the axis of the tube so that the electrons over the initial and returning paths may be unimpeded. The electrode 25 is operated at a potential slightly negative with respect to the electrode 12 so that electrons in the space between the anode 12 and the electrode 25 are driven to the collector 20.

Referring to Figure 2 which shows a modification of my invention, the cylindrical electrode 20 is replaced by a frusto-conical electrode 30 which is likewise operated at a positive potential with respect to the anode 12 to collect electrons thereon. Immediately adjacent the conical collecting electrode, I prefer to provide a frusto-conical electron permeable apertured electrode, such as a formed wire mesh screen 31, which may be operated at a positive potential with respect to the electrode 30. While I have shown in Figure 1 the output impedance being located in the circuit of the electrode 20, additional advantages may be obtained either in the structure of Figure 1 or Figure 2 by connecting the output impedance 21 directly to the cylindrical screen 23 or conical screen 31 whereupon the screen may be operated at a slightly higher potential than the adjacent electrode and as the conical electrode 30 which in turn is at a slightly higher potential than the anode 12. In the structure of Figure 2, secondary electrons emitted by the anode 12 flow through the apertures of the screen 31 and impinge the electrode 30 liberating further secondary electrons which are then collected by the screen electrode 31 and utilized in developing the output signal across the impedance 21. The conical form of this electrode is found to be conducive to more efficient emission of secondary electrons and more uniform collection of these electrons. The inner surface of the cylindrical or conical electrodes may be roughened such as by sand blasting or etching to increase the uniformity of secondary electron emission.

I have shown in Figure 3 a further modification wherein the electrode 12 is of smaller diameter but performs the same function as described, except I provide an initial electron collecting or second multiplying electrode of annular form surrounding the anode 12 as shown at 35. Secondary electrons emitted from the anode 12 are made incident thereon for collection or for further secondary electron multiplication. Obviously, in view of the structures of Figures 1 and 2, a wire mesh electrode 36 may be provided immediately in front of the electrode 35 for final electron collection when the annular electrode 35 is operated as a second secondary electron emitter.

In each of the modifications of my invention described above, the electrons returning from the target are accelerated to a velocity determined by the potential of the anode 12 and incident thereon at that velocity. Secondary electrons emitted

by the anode 12, however, have relatively low initial velocity and are more readily affected by the electrostatic field developed between the anode 12 and shield 25 by the collecting electrode. In addition, returning electrons follow non-symmetrical paths surrounding the initial path and are more subject to small potential gradients developed by the collecting electrode. Consequently, these secondary electrons may be collected readily without introducing high potential gradients in the electron beam path.

From the foregoing description relating to each of Figures 1, 2, and 3, it will be noted that the collecting electrode or the second secondary electron emitter symmetrically surrounds the initial electron beam path. In effect the conical structure shown in Figure 2 is a modification intermediate of those of Figures 1 and 3, the cylindrical structure 20 being expanded at the end nearer the target to obtain the conical structure 30, this in turn being further expanded to form the annular structure 35. Consequently, each of these electrodes whether in the form of a cylinder, frustum of a cone or annular has a surface which is formed as a surface of revolution about the initial electron beam path. The imaging aperture 13 must be of exceedingly small diameter such as two-to-three thousandths of an inch to prevent returning electrons from penetrating this aperture. Furthermore, the minimum diameter of the electrode formed as a surface of revolution must be sufficient in accordance with my invention to allow the returning electrons to reach the anode 12. I have found that a minimum diameter of one-quarter of an inch will allow substantially all of the returning electrons to reach the anode. Furthermore this limiting dimension is controlled in part by the diameter of the imaging aperture 13. Consequently the minimum diameter of the surface of revolution may be specified as a function of the limiting aperture diameter. For example, I have found this minimum diameter to be preferably at least 75 to 100 times the beam limiting aperture diameter. Consequently, the effective diameter of the anode 12 utilized for secondary electron emission is likewise of similar value and consequently with the surface of revolution electrode surrounding the anode as shown in Figure 3, the anode 12 must be at least 75 to 100 times the diameter of the limiting aperture therein.

I claim:

1. Television transmitting apparatus comprising an evacuated envelope, an electron source within said envelope, a target oppositely disposed from said source adapted to receive electrons from said source, magnetic means to develop a magnetic field extending from said cathode to said target, an anode having an electron beam limiting aperture between said source and said target, magnetic means between said anode and said target to deflect electrons passing through said limiting aperture over the surface of said target whereby electrons not reaching said target are returned to said anode along paths substantially coincident with but surrounding the initial path of electrons flowing toward said target, and means including an electrode positioned about said initial path and between said anode and said magnetic means to intercept secondary electrons developed by electrons returning from said target incident on said anode.

2. Television transmitting apparatus including an evacuated envelope, a cathode for liberating electrons within said envelope, a target oppo-

sitely disposed from said cathode, a magnetic coil surrounding the space between said cathode and said target, an anode having an electron beam forming and limiting aperture in the path of electrons issuing from said cathode to direct electrons along an initial path toward said target, wholly magnetic means to deflect the electron beam in two mutually perpendicular directions over the surface of said target and cause the electrons not reaching said target to return to said anode along paths substantially parallel and surrounding the initial electron beam path, and electrode means wholly removed from the paths of returning electrons and surrounding said paths and lying between said anode and said magnetic means to intercept secondary electrons developed by said returning electrons without impingement of said returning electrons on said electrode means.

3. Television transmitting apparatus comprising an evacuated envelope enclosing an electron emitting cathode, an oppositely disposed target to intercept a portion of the electrons emitted by said cathode, a beam limiting apertured anode of secondary electron emitting material interposed between said cathode and target to limit the quantity of electrons flowing toward said target and to intercept electrons not reaching said target, means to develop a longitudinal magnetic field wholly enveloping the space between said anode and said target, magnetic means to deflect electrons approaching said target over the extended surface thereof, an electrode having a surface of revolution surrounding said beam positioned between said anode and said magnetic deflection means to intercept secondary electrons deflected on said anode, said electrode being wholly removed from the path of electrons flowing between said anode and said target and between said target and said anode.

4. Television transmitting apparatus comprising a tube having an electron emitting cathode to develop a stream of electrons, an oppositely disposed target electrode, a secondary electron emitting anode having a beam limiting aperture to form said electrons into a beam having a minimum diameter at said aperture, magnetic means to develop a longitudinal magnetic field with lines of force extending from said cathode to said target, wholly magnetic means to deflect said beam over the surface of said target for collection in accordance with electrostatic image developed thereon and to direct electrons not reaching said target to said anode along paths surrounding the initial path of said beam to develop secondary electrons thereon, an electrode having a surface of revolution about said initial beam path wholly removed from said surrounding paths and between said anode and said magnetic deflection means to intercept said secondary electrons and develop additional secondary electrons, and perforated electrode means substantially coextensive with said electrode having a surface of revolution and between said electrode and said surrounding paths to collect said additional secondary electrons.

5. Apparatus for television transmission as defined in claim 4 including an apertured secondary electron intercepting electrode positioned between said electrode having a surface of revolution and said magnetic deflection means, said intercepting electrode extending transversely to said initial beam path.

6. Apparatus for television transmission comprising an evacuated envelope, an oppositely dis-

posed cathode and target electrode within said envelope, a magnetic coil surrounding said envelope to develop a magnetic field having longitudinal lines of force extending substantially from said cathode to said target to direct an electron beam along an initial path toward said target, an anode having an aperture in alignment between said cathode and target to form and direct an electron beam toward said target, wholly magnetic means between said anode and target to scan said beam over the surface of said target and to direct electrons not reaching said target along returning paths surrounding said initial path to said anode, a cylindrical electrode wholly removed from said paths and surrounding said paths between said anode and said magnetic means to receive secondary electrons developed by said returning electrons on the surface of said anode and means comprising an apertured electrode between said cylindrical electrode and said magnetic means to prevent said developed electrons from reaching said target.

7. Television transmitting apparatus comprising an evacuated envelope enclosing a cathode and target electrode, an apertured anode of secondary electron emitting material adjacent said cathode to develop and direct an electron beam toward said target, a secondary electron emitting cylindrical electrode immediately adjacent said anode and exposed to the surface thereof nearer said target, an electron collecting electrode substantially coextensive with and within said cylindrical electrode, magnetic means to scan electrons passing through said apertured anode over the surface of said target in the presence of a longitudinal magnetic field whereby electrons not reaching said target are returned along paths substantially parallel with and surrounding said electron beam without impinging upon said cylindrical and coextensive electrodes.

8. Television transmitting apparatus comprising an elongated envelope having a cathode and target adjacent opposite ends thereof, an intermediate electrode structure comprising an apertured anode and an apertured secondary electron shielding electrode in the order named between said cathode and target, a frusto-conical electrode between said electrodes with its apex adjacent said anode to receive electrons from said cathode passing through said apertured electrodes but not reaching said target and a perforated electron collecting electrode substantially coextensive with and lying within said frusto-conical electrode to collect electrons for development of television signals.

9. Television transmitting apparatus comprising an elongated evacuated envelope, a cathode, oppositely disposed target within said envelope, magnetic means extending substantially over the space between said cathode and said target to constrain electrons as a beam flowing between said cathode and target, an apertured anode of predetermined area aligned with its aperture in the path of said beam, an annular electrode surrounding said anode having a minimum diameter at least 75 times the diameter of said anode aperture to collect secondary electrons developed by the portion of said beam not reaching said target and impinging on said anode.

10. Apparatus as claimed in claim 9 including a perforated electron collecting electrode in a plane substantially parallel with and directly adjacent said annular electrode.
